UNITED STATES PATENT OFFICE.

LINA BARKLEY, OF MONROE, LOUISIANA.

DESIGN FOR A FAN.

SPECIFICATION forming part of Design No. 25,382, dated April 14, 1896.

Application filed February 15, 1896. Serial No. 579,455. Term of patent 34 years.

To all whom it may concern:

Be it known that I, LINA BARKLEY, a citizen of the United States, residing at Monroe, in the parish of Ouachita and State of Louisiana, have invented and produced a new and original Design for a Fan, of which the following is a specification.

Reference is to be had to the accompanying drawing, forming a part hereof, in which the figure represents a front perspective view of a fan embodying my new design.

The leading feature of my design consists in the fan having a series of overlapped cir-

cular members at its periphery, giving a scalloped effect.

Another feature of my design resides in the central figure having a scalloped edge and having radial divisions on its face.

I claim—

The design for a fan herein shown and described.

LINA BARKLEY.
